ATTORNEY.

UNITED STATES PATENT OFFICE.

THOMAS M. MCKEE AND SILAS B. SAFFELL, OF INDIANAPOLIS, INDIANA,
ASSIGNORS TO NATIONAL ADJUSTABLE CHAIR COMPANY, OF GREEN-
FIELD, INDIANA, A CORPORATION OF INDIANA.

SWINGING CHAIR.

SPECIFICATION forming part of Letters Patent No. 695,225, dated March 11, 1902.

Application filed May 29, 1901. Serial No. 62,322. (No model.)

To all whom it may concern:

Be it known that we, THOMAS M. MCKEE and SILAS B. SAFFELL, citizens of the United States, residing at Indianapolis, in the county 5 of Marion and State of Indiana, have invented certain new and useful Improvements in Swinging Chairs; and we do declare the following to be a full, clear, and exact description of the invention, such as will enable others skilled in the art to which it appertains to make and use the same, reference being had to the accompanying drawings, and to the letters of reference marked thereon, which form a part of this specification.

15 Our invention relates to adjustable folding chairs that are designed to swing and also to rebound, the object being to provide an improved chair and supporting means that may be useful and convenient, particularly for 20 children, and in larger sizes for invalids and those who may be crippled, as well as for persons who may desire a chair of this character, a further object being to provide a simple, durable, and cheap article for the above 25 purposes that may be adapted to be shipped as a knockdown article of furniture and be easily set up and also be taken apart without the use of any tool whatever in so doing.

With the above objects in view the invention 30 consists in the parts and in the combination and arrangement of parts embraced in the details of construction, as will be hereinafter particularly described, and pointed out in the claims.

35 Referring to the drawings, Figure 1 represents the article perspective as we construct it and set up ready for use; Fig. 2, a fragmentary side elevation showing the manner in which the chair may be adjusted and fastened as a reclining-chair and also showing 40 positions it may assume when swinging; Fig. 3, a fragmentary perspective view of an upper portion of the supporting-frame for the chair; Fig. 4, a sectional detail view showing 45 the manner in which parts of the frame are connected; Fig. 5, a sectional detail view showing parts of the frame partly disconnected; Figs. 6 and 7, fragmentary detail views 50 of parts of the article that will be fully described hereinafter.

Similar reference characters in the several figures of the drawings indicate like parts.

In construction we employ a chair and hanging members therefor that may be partly disconnected and the parts folded together, so 55 as to be compact for storage or shipment, and a supporting-frame that may likewise be partly disconnected and folded together compactly. The supporting-frame comprises four similar upright leaning posts A A' A² A³, connected together at their upper ends by a beam B, the latter having near each end thereof a pair of vertical slots e e, one at each side thereof, and into each slot an upper end of a leaning post is fitted removably, the posts being 60 coupled together in pairs of two each by means of a fulcrum-rod f, extending across the under side of the beam B, supporting the same. At the middle portion of each pair of legs so coupled by the rod f the pair are connected 65 by a spreading bar C, each bar being connected at one end thereof by a pivot a to one leg and at the other end thereof by a hook-notch d, engaging a stud b, projecting from the other leg, to which the bar is thus detachably 70 connected, the bar being adapted to move radially about its pivot, as at C'.

At the under side of the beam B, near each end thereof, between the two pairs of legs described, are hooks D D' or eyes supporting 80 closely-coiled springs E E', each spring having a hook g or an eye at each end thereof. Yokes F F' are detachably connected to said springs, and to the yokes we detachably connect four suspending-bars H H' H² H³, to 85 which the chair is pivotally connected. Each spring E or E' is provided with a limiting-link G or G', extending through the spring somewhat and suspended by the hook D or D' and embracing the yoke F or F', so that 90 the yoke may draw the spring until the end of the link is reached and no more, thus limiting the extending action of the spring. The suspending-bars have each near the upper end thereof a recess l, and below this a perforation m, by which it is suspended to the yoke F or F', each of the latter consisting of 95 two diverging stems h h, each stem having a lateral branch i, extending in the recess l to the opposite side of the bar, and a longitudinal 100

branch *j*, at the end of which is a hook *k*, inserted into the perforation *m*. The chair has arms *I* *I'*, at the ends of which they are connected to the suspending-bars by means of 5 pivot-studs, which also connect to the arms a suitable chair-back *J* and front corner-posts *K* *K'*, the back and the corner-posts being also pivoted to a suitable seat-frame *L*, the pivoting members *n* being suitably composed 10 of bolts having slotted heads and straight bodies with screw-threads thereon. A foot-board *M* is secured to the lower ends of the posts *K* *K'*. A link chain *N* is attached to the lower end *p* of a side member of the back 15 *J* and also is attached to an arm *I* or *I'*, so as to be taut when the chair is in the position shown in Fig. 1, thereby preventing the top of the back from tipping forward undesirably far. A pin *q* projects from said end *p*, 20 which may be engaged by the chain-links when it is desired to fix the chair in a reclining condition, as indicated in Fig. 2. A chain *O* is also connected to the back *J* and to a suspending-bar *H* or *H'*, to which the back is 25 pivoted, to limit the descent of the top of the chair-back when in reclining position.

In practical use a person may sit in the chair and swing as well as spring vertically, the chair being capable of movement on its 30 pivots, so as to assume the reclining positions shown in Fig. 2 or the sitting position indicated by dotted lines in the same view, the main parts, as the back *J'*, seat *L'*, and foot-board *M'*, being designated as those which 35 change positions affecting the posture of the occupant.

It will be readily seen that it will require no tool in either taking down or setting up this apparatus, which is a great advantage in any 40 residence, and any unskilled person may perform the acts with ease. In taking the chair down for storage or removal the yokes *F* *F'* may be disconnected from the suspending-bars and also from the springs. Then the chair 45 may be extended to a reclining position and the suspending-bars extended alongside the same. Then the bars *C* may be disconnected at one end and extended alongside the post, to which it is pivoted. Then by drawing together 50 the lower ends of each pair of posts, as *A*² *A*³, the upper ends thereof will assume the positions shown in Fig. 5, releasing the beam *B*, which had been clamped thereby, and withdrawing the beam the posts may 55 then be drawn together compactly side by side.

Having thus described our invention, what we claim, and desire to secure by Letters Patent, is—

60 1. A swinging chair including two pairs of leaning posts, a beam detachably clamped to the posts, a pair of spreading bars each pivoted to a post and detachably connected to an opposing post, a fulcrum-rod connecting each

pair of posts below the beam, a pair of springs 65 connected with the beam, limiting-links for the springs, yokes connected with the springs, suspending-bars connected detachably to the yokes, and a chair connected to the suspending-bars.

2. In a swinging chair, the combination of the supporting-frame, the yokes, yielding members connecting the yokes with said frame whereby to support the yokes, the suspending-bars detachably connected to said 70 yokes, the chair-arms pivoted to said bars, the back pivoted to said arms, the front posts pivoted to said arms, the seat-frame pivoted to said back and to said front posts, the pin attached to said back at the lower portion 75 thereof, and the link chain connected to one of said arms and also to said back near said pin.

3. In a swinging chair, the combination of the two pairs of leaning posts each pair having a fulcrum-rod and the spreading-bar, the beam detachably clamped by said posts at said rods, the springs connected with said beam, the limiting-links for said springs, the yokes connected with said springs, the suspending-bars having the recesses and the perforations and thereby detachably connected to said yokes, the chair pivoted to said suspending-bars and having the chain connected to an arm thereof and to the back thereof and 90 also having the chain connected to the back thereof and to one of said suspending-bars, whereby said chair may simultaneously swing and rebound and alternately assume sitting and reclining positions and also be fixed in a 95 reclining position, substantially as set forth.

4. In a swinging chair, the combination of the two pairs of leaning posts, the beam, the hooks attached to the beam, the springs connected to said hooks, the yokes each comprising 105 two diverging stems having each a lateral branch and a longitudinal branch having a hook at the end thereof, said yokes being connected to said springs, the suspending-bars connected to said yokes, and the chair connected to the suspending-bars.

5. In a swinging chair, the combination of the two pairs of leaning posts, the beam, the hooks attached to the beam, the suspending-bars having each the perforation and having 115 also the recess between the perforation and the upper end of the bar, and the yoke connected to the spring and having the diverging stems in said recesses and also extending into said perforations, and the chair connected to said suspending-bars.

In testimony whereof we affix our signatures in presence of two witnesses.

THOMAS M. MCKEE.
SILAS B. SAFFELL.
